UNITED STATES PATENT OFFICE.

WILLIAM TWEEDDALE, OF BROOKLYN, NEW YORK.

FASTENER FOR MEETING-RAILS OF SASHES.

SPECIFICATION forming part of Letters Patent No. 372,645, dated November 1, 1887.

Application filed April 14, 1887. Serial No. 234,793. (No model.)

To all whom it may concern:

Be it known that I, WILLIAM TWEEDDALE, a citizen of the United States, residing at Brooklyn, in the county of Kings and State 5 of New York, have invented new and useful Improvements in Sash-Fasteners, of which the following is a specification.

This invention relates to improvements in sash-fasteners, as set forth in the following 10 specification and claims, and illustrated in the accompanying drawings, in which—

Figure 1 is a vertical central section of a sash-fastener. Fig. 2 is a view similar to Fig. 1, the parts of the fastener being locked. Figs. 15 3 and 4 are detailed views of a fastener.

Similar letters indicate corresponding parts.

In the drawings, the letter A indicates a lower window-sash, and B an upper window-sash. To one sash is secured a case or housing, C. A toothed block, D, is adapted to pass 20 into and out from a chamber, c, in the case C. To the other sash is secured a vertical toothed stud or arm, G. The block or piece D is moved by a spring, F, toward and into engagement with the stud or arm G, and said 25 block D is tapped for the reception of a screw-shank, e, having a head, E. The head E enables the block D to be moved out of engagement with the stud or arm G, so that the sashes 30 A B may be moved to open the window. By having the teeth on said block and stud or arm provided with inclined faces, as seen in the drawings, said teeth will glide over one another during the closing of the sashes A B, but said 35 teeth will lock the sashes against being opened, so that the toothed block D must be moved

out of engagement with the stud or arm G, by means of the head E, before the sashes A B can be opened. An inclined head, g, on the toothed stud or arm G, adapted to glide over 40 an inclined or rounded end or shoulder, h, on the toothed block D, is adapted to start the block and stud or arm in gliding past one another during the closing of the sashes.

The toothed stud or arm G is tapped, as at 45 i, for the reception of the screw-shank e. When the sashes are closed, the screw-shank can be caused to engage the toothed block D with the toothed stud or arm G, so as to lock said parts together to secure an effective closing or locking 50 of the sashes A B.

What I claim as new, and desire to secure by Letters Patent, is—

1. The combination, with a toothed stud or arm, G, and a toothed block, D, of a screw-shank, said stud and block being both tapped 55 for the reception of said screw-shank, and said block being made movable toward and from the stud or arm, substantially as set forth.

2. The combination, with a toothed stud, G, 60 and the toothed block D, of a spring adapted to move said block toward the stud, said stud and block both tapped for the reception of a screw-shank, substantially as set forth.

In testimony whereof I have hereunto set 65 my hand and seal in the presence of two subscribing witnesses.

WILLIAM TWEEDDALE. [L. S.]
